FEEDING CHAIR TOY

Jesse D. Horowitz, New York, N.Y., assignor to De Luxe Reading Corporation, Elizabeth, N.J., a corporation of New Jersey

Filed Jan. 26, 1965, Ser. No. 83,584

Term of patent 3½ years

(Cl. D34—15)

FIG. 1

FIG. 3

The broken line showing of a food dish is for illustrative purposes only.

I claim:

The ornamental design for a feeding chair toy, substantially as shown and described.
